UNITED STATES PATENT OFFICE.

SAMUEL MODERN AND MAX MOSKOWITZ, OF NEW YORK, N. Y.

DESIGN FOR A HANDGRIP.

Application filed April 25, 1927. Serial No: 21,724. Term of patent 3½ years.

To all whom it may concern:

Be it known that we, SAMUEL MODERN and MAX MOSKOWITZ, citizens of the United States of America, residing at New York city, in the county of New York, and State of New York, have invented a new, original, and ornamental Design for a Handgrip, of which the following is a specification, reference being had to the accompanying drawing, forming part thereof.

In the drawings:—

We claim:—

The ornamental design for a hand grip, as shown.

SAMUEL MODERN.
M. MOSKOWITZ.
